UNITED STATES PATENT OFFICE.

JAMES J. HARKINS, OF PITTSBURGH, AND OTTO F. ORMAN, OF MCKEESPORT, PENNSYLVANIA, ASSIGNORS OF FOUR-FIFTHS TO SAID HARKINS AND ONE-FIFTH TO SAID ORMAN.

APPARATUS FOR THE MANUFACTURE OF SEAMLESS STEEL TUBES.

Application filed December 2, 1919. Serial No. 341,931.

To all whom it may concern:

Be it known that we, JAMES J. HARKINS and OTTO F. ORMAN, citizens of the United States, and residents, respectively, of Pittsburgh and McKeesport, in the county of Allegheny and State of Pennsylvania, have invented a new and useful Improvement in an Apparatus for the Manufacture of Seamless Steel Tubes, of which the following is a specification.

This invention relates to an apparatus for the manufacture of seamless steel tubes by means of rolls, tables, and other appurtenances, and is called a seamless steel tube rolling mill. It is designed primarily to increase the production, and incidentally to reduce loss by oxidation and scrap.

In the manufacture of seamless tubing, an ingot is "pierced" to form a longitudinal hole therethrough in what is known as a "piercing mill." The ingot, after being pierced, is termed a shell, and is subjected to the action of a pair of rolls and a plug, by means of which the shell is eventually drawn out into a tube.

According to the operation of mills now generally in use for the production of seamless tubing, the ingots are moved longitudinally from the piercing mill to a transfer table. After being run out on the transfer table, they are moved transversely to one side until they are positioned in front of a "two high" rolling mill having a single groove formed therein for drawing out the pipe. The shell is then fed longitudinally through the rolls and over an expanding plug. After the full length of the shell has been passed through the rolls once, the rolls are spread apart, and the ingot or tube passed back through them in the reverse direction. During the reverse passing of the shell, the spaced apart rolls do not engage it to roll it out. After the entire shell has been thus passed reversely through the rolls, the rolls are closed and the shell is given a second pass. This operation of passing and re-passing the shell through the rolls is carried out several times until the tube has been drawn to the desired gauge and finish, after which another ingot is operated upon in a similar manner.

The width of the floor space required for such mill has been found to be quite large, and considerable time and labor is lost in

the passing and re-passing of the tubes through the mill. Furthermore, it has been found that the plug used for expanding the tube after the tube passes through the rolls (to expand the tube sufficiently to enable the groove of the rolls to engage the tube on the next pass) often ruptures the metal, necessitating that the entire shell or tube be scrapped. In a mill of this type, the shell also loses most of its heat before it is completely rolled, and the last steps have to be performed when the metal is relatively cold.

It is an object of the present invention to eliminate the usual transfer table and the necessity for re-passing the tube through the rolls by having a series of two or more pairs of rolls arranged in tandem, through which the ingot is successively passed.

A further object of the invention is to eliminate the use of a plug for expanding the tube after a pass through the rolls by working the metal down from the outside, such reduction from the outside being termed a "breaking down" process.

A further object of the invention is to provide a mill in which tubes of various diameters may be rolled without inserting new rolls or changing the apparatus used for transferring the shell from one pair of rolls to the next.

These and other objects of the invention will be apparent from the description thereof.

According to the invention, a receiving table is positioned in longitudinal alignment with the piercing mill. This receiving table is provided with rollers to assist in supporting and advancing the ingot, and a pusher carried by a trolley supported above the rollers is preferably provided for positively feeding the ingot from the receiving table. At the end of the receiving table most remote from the piercing mill is a thrust bearing adapted to rotatably clamp a plug bar which extends the length of the receiving table and the end of which has a plug which assists in the operation of the piercing mill. Means are provided for clamping the plug end of the bar when the clamps at the thrust bearing end of the plug are released to permit the tube to pass through the thrust bearing on to a series of troughing rolls, or on to a rack provided at one side of the troughing rolls, the trough-

ing rolls and rack being transversely movable.

A pair of two high tube drawing rolls having complementary grooves of graduated sizes therein is arranged at the end of the troughing rolls and rack, the arrangement being such that by moving the trough rolls and rack transversely, the tube may be fed through any desired pair of grooves in the rolls, depending on the gauge of the tube it is desired to produce. Arranged behind the first pair of rolls is a second receiving table which is also movable transversely in order to selectively receive the tube from the groove in the first pair of rolls, and feed it into the proper grooves of the next pair of rolls which is positioned immediately behind this second receiving table.

Means which we term an "edging machine" is provided on this table for rotating the tube a quarter turn before it is fed through the second set of rolls. This table is also provided with a plug bar clamp for supporting one end of the plug bar. There may be any desired number of such tables arranged in longitudinal alinement and having drawing rolls placed between them. After passing through the last pair of drawing rolls, the tube passes on to a plug bar supported over a "run-out" table. This table is provided with means for withdrawing the plug bar from the tube, and with automatic means for moving the tube to one side after the plug bar has been so withdrawn.

While the foregoing describes briefly the arrangement of parts which we use in connection with our invention, the construction and operation may be better understood by reference to the accompanying drawings, in which:

Fig. 1 is a diagrammatic top view of a mill involving our invention, showing the apparatus between the piercing mill (not shown) and the second set of drawing rolls;

Fig. 2 is a diagrammatic plan view of the apparatus from the second pair of drawing rolls to the discharging means or run-out table, and constitutes a continuation of the apparatus shown in Fig. 1;

Fig. 3 is a side elevation of the apparatus shown in Fig. 1;

Fig. 4 is a side elevation of the apparatus shown in Fig. 2;

Fig. 5 is an enlarged plan of the apparatus between lines 1—1 and 2—2 of Fig. 1;

Fig. 6 is a longitudinal vertical section along the center of Fig. 5;

Fig. 7 is a plan view on a larger scale of the apparatus between lines 2—2 and 3—3 of Fig. 1;

Fig. 7' shows a transverse section on line 7—7' of Fig. 7;

Fig. 8 shows partly in section and partly

in elevation a side view of the apparatus shown in Fig. 7;

Fig. 9 is a plan view on a larger scale of the apparatus between lines 3—3 and 4—4 of Figs. 1 and 3;

Fig. 28 is a similar transverse section on line 28—28 of Fig. 5;

Fig. 29 is a similar transverse section on line 29—29 of Fig. 5 showing the construction of the jaws for supporting the plug bar when the thrust bearing has been unclamped therefrom to permit the shell to be passed on to the feed trough or receiving rack;

Fig. 30 is an end elevation of the receiving table;

Fig. 31 is a horizontal section on line 31—31 of Fig. 24, but on a large scale;

Figs. 32 and 33 are details of the thrust bearing mechanism;

Fig. 34 shows a plan view of one of the clamping jaws employed in the mechanism shown in Fig. 29;

Figs. 35 and 36 are details of the operating handle of the edging machine;

Fig. 37 is a transverse section on line 37-37 of Fig. 10;

Fig. 38 is a similar section on line 38-38 of Fig. 10, showing an end view of the 10 plug bar clamp;

Fig. 39 shows in detail the shell gripping mechanism employed in the edging machine shown in Fig. 37;

Fig. 40 shows in detail the plug bar clamp 15 used in the apparatus shown in Fig. 38.

Figs. 41 and 42 show details of the edging machine;

Fig. 43 shows in detail an automatic plug bar holder which may be raised and lowered when it is desired to supply a new ball or plug to one of the plug bars;

Fig. 44 is a vertical section of the apparatus shown in Fig. 39;

Fig. 45 is a transverse section on line 25 45-45 of Fig. 11;

Fig. 46 is a transverse section on line 46-46 of Fig. 11;

Fig. 47 is a transverse section on line 47-47 of Fig. 11, showing the mechanism 30 for raising the hoods or covers on the run-out table;

Figs. 48 and 49 show a side and an end view respectively of a cross head used for reciprocating the plug bar on the run-out 35 table; and

Fig. 50 shows the position of a plug between the rolls for effecting a breaking down process of tube rolling.

In the drawings in which the piercing 40 mill is not shown, this being of any known or preferred form, A is the receiving table, B the thrust bearing, C the transversely movable trough rolls and receiving rack, D the first pair of rolls, E the second receiving 45 table, F the second pair of rolls, G the third receiving table similar in all respects to E, and of which there may be any desired number, arranged alternately with drawing rolls, H is the last pair of drawing 50 rolls in the train, and I is the run-out table.

The first receiving table A is shown assembled, together with thrust bearing D in Figs. 5 and 6, and its detail construction is shown in Figs. 19, 20, 21, 22, 23, 25, 26, 55 27, 28, 29, 30 and 34. Referring particularly to Fig. 30, which shows that end of the table adjacent the piercing mill, 1 is a supporting frame having horizontal flanges 2 at the base thereof and which are bolted to base 17. The top of support 1 is recessed as shown (see detail Fig. 19) to receive corresponding projections 1' on the vertically adjustable trough support 3 having a V-shaped depression in which is secured one 60 end of the trough 15. Underneath the cross

projections are a pair of bolts 3' for effecting the vertical adjustment of the supporting member 3 to accommodate tubes of different diameters. Secured at 3'' across the top of the member 3 is a substantially 70 semi-circular hood or cover 4.

Slidably guided on the base 17 is a frame 5 (see Figs. 6 and 29). The central portion of the top of the frame 5 is provided with a longitudinal V-shaped depression 5a 75 (see Fig. 29) which forms a slidable support for the trough 15. At each side of this longitudinal groove and slideable in suitable guideways on the top of frame 5 are oppositely movable jaw bars 14 having 80 jaw portions 14a (see Figs. 29 and 34). Bolted to a depending side 5''' of the frame 5 is a bracket 10'' on which is mounted a cylinder 10 having a piston rod 10' reciprocable therein. This piston rod 10' is 85 pivotally connected to a lever 11 carried on a rock shaft 12 journaled in the frame 5, which shaft has its opposite ends provided with bell cranks 13. The upright arms of the bell cranks 13 are pivotally connected 90 to the ends of one of the movable jaws 14 while the horizontal arms connect at 13' to similar bell cranks 13a on a rock shaft 12a. The vertical arms of these cranks 13a are 95 similarly connected to the ends of the other jaw bar 14. It will be obvious that upon pressure being communicated to the cylinder 10, the jaws 14 will be reciprocated toward and from each other. This is for a purpose to be hereinafter described.

At 5' (see Fig. 6) on the frame 5, is a lug to which is secured the free end of a piston rod 22 which is reciprocable by means of a cylinder 18 secured to the frame 17. A forked lever 20 is also mounted on the rod 22 for reciprocation therewith (see Figs. 6 and 28). At 19 is a cover slidable along the trough 15, this cover having laterally extending lugs 19' projecting at each end thereof. The arms 20' of the fork 20 are movable between the lugs. When the element 20 is reciprocated, the forked arms can move the distance between the lugs 19' before they move the cover, hence the cover is only moved through a fraction of the distance of movement of the forked arms.

Arched over the cylinder 18 and secured to the base 17 is a vertical support 21 having a transverse channel across the top thereof in which operate sliding wedges 23 and 24 (see Fig. 27). On these wedges rests a supporting block 25 to which is secured the other end of the trough guide 15. To the supports 25 are also secured one end of truss members 30 across which is journaled a trough roller 39. Projecting laterally from block 25 is an extension 25' to which is secured a shelf 26 on which is journaled at suitable intervals a line shaft 27'. On the base 31 in transverse channels 31' therein 125

are other wedges 23 and 24 on which rest other supporting blocks 33 and 35 having lateral shelf supporting extensions 33' and 35' respectively, for the shelf 26.

5 To the block 33 are secured frame members 30 and 32 (see Fig. 20), the frame members 32 also being supported by block 35 and an intermediate member 34. On the tops of the members 33, 34 and 35, are secured sections of a trough, such as 36, 37 and 38, respectively. Between the sections of trough are other guide or feed rollers 39. All of the rollers 39 are driven in unison by gearing 27 from the line shaft 27'. The line shaft, in turn, is driven by a motor 42 pivotally supported, as shown in Fig. 26. Connected to wedges 23 beneath blocks 25 and 35 are threaded rods 56 having their outer ends supported in brackets 55. On the projecting outer ends of each of these rods is a crank 57 having a threaded hub. By operating the cranks 57 which act as nuts, the wedges 23 and 24 will ride on each other to raise and lower the trough and rolls.

25 The motor 42, being supported on trunnions, can be maintained in proper driving relation to the gearing which drives shaft 27 when the shaft 27 is raised and lowered with the shaft 26. This raising and lowering of the trough and rolls accommodates tubes of different sizes.

Supported above the feed and guide rolls and the trough comprising the receiving table, on standards 43 and brace members 43' (see Figs. 6, 22 and 23), is a pusher frame 95 comprising longitudinally spaced apart angle bars 54 having racks 49 arranged therealong. Suspended from the frame is a cover 44 having a slot extending the length thereof along its top. A carriage or trolley 92 is supported on the angle bars 54, the trolley comprising a frame 47, driving pinions 49' on a shaft 48 in the frame, guide rollers 48' on shaft 48, and other guide rollers 52 on studs 53, the guide rollers 52 engaging the under side of the angle bars to hold the carriage on the tracks.

A reversible motor with gearing is provided on the trolley for driving the pinions 49' to move the carriage along the track. A transverse bar 50 extends across the carriage near the top thereof. Pivotally suspended from a cross shaft 55 in the carriage is a pusher lever 51. By means of this arrangement, the bar 50 acts as a stop to limit the swing of the push lever in one direction so that, upon the carriage being moved in the direction of travel of the shells from the piercing mills, it will engage the rear end of such shells to push them. By reason of the lever being capable of swinging in the opposite direction, the forward ends of the shells will merely ride under the lever, and it therefore will not form any obstruction to the advance of the shells.

At the end of the receiving table A and supported on the base 31 is the thrust bearing B for rotatably holding the ball or plug bar, and which is so constructed as to permit the bar to be released to permit of the shell 70 being passed longitudinally off the bar at the end opposite the plug or ball. The thrust bearing, indicated generally by the reference numeral 93 (see Figs. 5, 6 and 24), is supported on a stand 65 having a cap 66 75 at the top thereof, which cap is preferably formed with an oil box 66'. Threaded within the interior of the round opening formed by the top of support 65 and the cap 66 (see Figs. 6 and 24) is an adjusting sleeve 80 75 having its rear end provided with a hand wheel. The interior of the adjusting sleeve 75 is provided with annular grooves and projections 63' in the grooves of which rotatably fit similar projections on the exterior of a slip-gear-sleeve 60' (see Fig. 6). The outer end of the gear-sleeve 60' is flanged, and surrounding the periphery of this flange is an annular toothed slip-ring 60 having pockets 59'' therein. Slidably supported by 90 the sleeve 60' are clamping jaws 58 adapted to be actuated by pivoted levers 59 having projecting ends 59' which extend into the pockets 59''. By rotation of the slip gear ring 60 while the sleeve 60' is stationary, 95 the jaws may be opened or closed, depending on the direction of rotation.

For permitting the ring to rotate with the sleeve or independently thereof, the apparatus shown particularly in Figs. 24 and 31 100 has been devised. This apparatus comprises a fluid pressure cylinder or jack 68 having a reciprocable piston rod 71, the outer end of which is bifurcated, as shown in Fig. 31. Across the two arms of the bifurcated end of this rod is a stationary non-rotatable hollow shaft 70. Journalled about the shaft is a pinion 62. Slidable in the hollow shaft 70 are opposed pins 72 and 73, and radially disposed with the shaft are pins 77. Extending from the top of the cylinder 68 is a frame member 74 having downwardly turned flanges, to which are secured grooved blocks 76 having oppositely inclined surfaces therein. Assuming the parts to be in the extended position shown in Fig. 24, the pinion 62 engaging slip gear ring 60 will rotate freely upon the hollow shaft when the slip ring rotates. Should pressure be applied to cylinder 68 to retract the piston rod 71, pin 72 would be forced inwardly, projecting radial pins 77 into an eccentric recess in the pinion 62, locking the pinion from rotation. Further transverse movement of the pinion 62 to retracted position turns the slip ring 60 to spread the jaws 58. Upon the piston rod being extended, the action is the converse, pin 73 serving to move pin 72 outwardly to permit the radial pins 77 to withdraw.

The plug bar is indicated at 61 and ex- 130

tends from the thrust bearing to a point beyond the end of the receiving table and adjacent the piercing mill.

Thus far, the operation of the machine is as follows. The ingot, passing through the rollers of the piercing mill, is rotated and elongated. Passing over the ball on the bar 61, the ingot is pierced to form the shell. During the time the metal is being pierced, the thrust bearing at B allows the plug and bar 61 to rotate, at the same time that it assumes the end thrust for the plug bar. With the aid of the troughed feed rollers 39, the shell is advanced until its completed length is on the plug bar and its end adjacent the thrust bearing. By means of cylinder 10, the clamp bars 14 are actuated to bring the clamping members 14^a into position to engage the ball end of the plug bar. Jaws 58 of the thrust bearing are then opened in the manner hereinbefore described, the ring 60 being rotated while the sleeve 60' is held against rotation.

When the jaws 58 are spread, the shell, with the aid of the power driven rollers 39, and, if necessary, pusher lever 51 of the trolley 92, will be pushed through the hollow end of the thrust bearing onto the apparatus hereinafter described. At the same time, piston 18 may be actuated to move the sliding frame 5 in the direction of the thrust bearing, withdrawing the ball on the end of the plug bar 61 from the piercing mill. Upon a new plug being applied to bar 61, cylinder 18 is then actuated to move the table 5 into extended position, clamps 58 in the thrust bearing are closed on the end thereof, and the jaws 14^a are retracted to release the ball end of the plug bar. The apparatus is then in position to receive the next shell from the piercing mill.

After passing from the receiving table through the thrust bearing, the shell must next be passed onto a suitable means for receiving the shell and feeding it to the rolls. In practice, it is contemplated that the rolls be provided with a series of graduated complementary grooves adjacent each other across the rolls, for the production of different gauge tubes. The first groove of this series is preferably in line with the thrust bearing and consequently it would be comparatively simple to devise a receiving trough adapted to receive the shell and pass it into the first groove. However, since the receiving trough must be capable of passing the shell through any one of the pairs of grooves in the rolls, it must be both transversely and vertically movable. It is therefore also necessary to provide a shelf adapted to receive the shells from the thrust bearing when the receiving trough is out of alignment with the thrust bearing.

The apparatus which we provide for receiving the shells from the thrust bearing

and feeding them into the rolls is indicated at C, while the first pair of rolls is shown at D. Figs. 7, 7', 8, 13, 14, 15, 16, 17 and 18 relate particularly to apparatus C. While it may be constructed in any desired manner, we have shown the apparatus as formed from structural metal. The trough itself comprises two parallel beams 101, bolted together and spaced by separators 102'. On top of these beams are mounted a plurality of guide and feed rollers 108 with their journals 106 and 135. The roller at the thrust bearing end of the frame is completely divided into sections 133 and 134. All of the rollers 108 and section 134 are positively driven through miter gears 113 driven from a shaft 112 carried at one side of one of the beams. This shaft 112 is rotated through gearing by a motor 115, also carried by the frame.

Extending from the side of the beams 101 opposite the motor 115, are a plurality of horizontal structural bars 104, on the outer ends of which is carried a beam 103. Extending transversely between beam 103 and the side of the trough frame are a plurality of relatively long rollers 141 and 142. These rollers are adapted to be driven by miter gears 138 on the projecting ends 135' of their shafts, which gears mesh with driving gears 138' on shafts 137 and 143 at different ends of the frame. Shafts 137 and 143 are carried at the side of beam 103 by journals 136, and are driven from a motor 140 through gears 139 which mesh with spur gears 139' on a lower shaft 153 (see Fig. 8). Shaft 153 carries a gear 139'' adapted to mesh with the driving pinion 139''' of the motor.

Secured between the beams 103 and the feed trough frame is a cylinder 155 having a piston rod 148, the outer end of which rod is connected with a cross head 145 having diagonal angle bars 147 attached thereto and slideable on guides 144. Connecting the ends of bars 147 is a pusher bar 146 having the block 146' thereon slideable in guides 144. Upon application of pressure to the cylinder, this pusher bar may be reciprocated transversely of the frame, thus providing means whereby shells delivered upon the side frame and rollers may be moved over to the feed trough. At the end of the frame opposite the thrust bearing is a stop 152 to prevent the shells from being carried too far on the receiving rack.

For receiving the shell and lowering it gradually onto the rolls 108, there is preferably provided a vertical cylinder 109 in the middle of the trough frame secured to a suspended frame 109'. In the cylinder is a plunger 109'' having a head 109''' which is V-shaped to carry plates 110 which project beyond the sides of the head sufficiently far to rest on supporting members 110' when in lowered position.

Underneath and between the beams 101 and carried thereby, is a cylinder 128 with a piston rod 129 connected to a cross head 130 made to slide between beams 101, which 5 beams act as a guide therefor. On the top of the cross head 130 is hinged a curved lever 131 with weight 132 on its lower end. This lever is so arranged that a shell riding forward will rock it downwardly out of the 10 path of travel, but the lever cannot move in the other direction past a vertical position. Thus, by operating the cylinder 128 to move rod 129, the lever 131 may be used to engage the ends of the shells to push them 15 along the trough into the rolls.

Beneath each end of the trough frame beams 101 are transversely extending guideways 127 having inclined guide surfaces 127^a (see Fig. 18). The beams 101 rest on 20 shoes 116 adapted to slide on these inclined ways. Extending across the plates 127 and supported in journals 119 are threaded rods 118, the projecting ends of which are provided with worm gears 121. Slidably supported in vertical guideways on the under 25 side of shoes 116 are nuts 117 which engage threaded rods 118. Upon rotation of the rods 118, the trough beam may thereby be reciprocated transversely, and at the same 30 time it is reciprocated, it will move vertically owing to the inclination of the guides 127^a. The nut 117 is vertically slidable to accommodate for the raising and lowering 35 of the shoes. The shafts 118 are rotated through worm gears 121 engaging worms 122 on a shaft 123 suitably journalled on supports 125 and having a spur gear 124 thereon which engages the driving pinion of a reversible motor 126. The beam 103 is 40 similarly supported on follower shoes 149 guided upon ways 150. Thus, the roller table and feed trough may reciprocate as a unit.

The first pair of drawing rolls D comprises housings 2^a in which are journalled the two rolls 151 having a plurality of graduated grooves. The first groove is in longitudinal and vertical alinement with the center of the thrust bearing while the others are necessarily at one side and higher than the thrust bearing.

In operation, supposing a tube is to be passed through the first groove, the apparatus is in the position shown in Fig. 7. The 55 shell, coming from the plug bar 61 through the thrust bearing, rocks the lever 131 out of its path and moves along on the feed rolls into the drawing rolls. For starting it into the drawing rolls, the lever 131 may be actuated to engage the end of the shell and push it. If, however, a tube of smaller diameter is to be formed, the feed trough is moved transversely by motor 126 opposite that pair of grooves corresponding to the 60 diameter of tube to be drawn. This trans-

verse movement raises the feed trough a sufficient distance to bring the feed trough on the same horizontal level as the groove. The shell, passing through the thrust bearing, then goes upon the roller table at the side 70 of the feed trough. Pusher 146 may then be actuated to move the shell transversely into the trough, after which it may be passed through the roll D.

Passing from the first pair of rolls, the 75 shell must pass over a second ball or plug and plug bar and be received on a second receiving trough. This receiving trough, which we call the intermediate trough, and plug bar is indicated at E. It is shown in 80 Figs. 9, 10, 10', and 35 to 45 inclusive.

The frame of the intermediate trough preferably comprises parallel I-beams 220" bolted together and spaced with separators 220' in a manner well understood. These 85 beams are supported on shoes 275 slidable on inclined guideways 273, and are operatively moved by screws 274, the construction and operation being identical with that 90 previously described in connection with the feed trough C. In this instance, however, there is no roller table, and hence the guides 150 are dispensed with.

On the beams 220" are bearings 221 in which revolve shafts 222 for rollers 223. The shafts 222 are extended at one side to 95 carry miter gears 224. On the sides of one of the beams 220" are brackets 268 providing bearings for a longitudinal line shaft 269, which shaft carries miter gears 224' to mesh with gears 224 for driving the rollers 223. The shaft 269 is driven through reduction gearing 271 by a motor 270 carried by the table frame. On top of beams 220" are also mounted several stands 225' 100 which provide supports for flat bars 226 forming the lower part of the guide troughs. Above these strips are covers 272.

On top of beams 220" and located about the middle, is the tube "edger," shown in 110 cross section in Fig. 10, and details of which are shown in Figs. 35, 36, 37, 39, 41, 42 and 45. This device is for the purpose of giving the tube a quarter turn before it is passed through the next roll. It comprises a stand 227 having a circular opening concentric to a plug bar indicated at 204. Seated on one end of stand 227 is a rotatable ring 228 and through the stand beneath the ring are slots 227' through which project jaws 229 and 115 230. Connected to jaw 230 is a lever 232 pivoted on the ring at 233. The other end of this lever is connected through links 231 and arm 234 with jaw 229 in such manner that downward movement of jaw 229 120 forces jaw 230 upwardly, so that both of them may grip the tube. Bolted to the support 227 is a bracket 239 having on its upper horizontal surface a trip-bar 238 which projects to one side. Pivoted at 237 125 130

on a bracket 235 secured to ring 228 is a hand lever 236 having a helical cam 236' (see Fig. 36) and a stop lug 236'' adapted to contact with trip-bar 238. The helical cam 236' engages in a notch on the projecting upper end of jaw 229.

In operation, the handle 236 is rotated, forcing jaws 229 and 230 into gripping relation with the tube and the ring 228 is rotated by pressure applied on handle 236 in the desired direction throughout the limit allowed by slots 227', which is preferably a quarter of a circle. This transmits a corresponding rotation to the tube. After having been turned 90 degrees, the jaws are released and the ring 228 turned back again to normal position.

During the rolling operation, a plug or ball 203' carried by a bar 204 is maintained between the rolls, as shown in Fig. 50, but in order to change the ball after each rolling operation, it is necessary to withdraw it. For this purpose, we provide a sliding clamp on the extreme end of the base, shown in Figs. 9, 10, 10', 38 and 40. Secured to the I-beams 201, is a flat plate 240' to the sides of which are bolted inverted L-shaped guide members 242. Slidable on this base 240' and in the guide members is a movable frame 241 having a rack 245 secured to the bottom thereof, the bottom being indicated at 250''. This rack projects into a slot 267 in the base 240'. Journalled in the I-beams at 261 is a transverse shaft 260 having a gear 259 thereon adapted to engage the rack 245. The outer projecting end of this shaft is provided with another pinion 262 adapted to engage rack 263 on the end of a piston rod 264, which rod is actuated by a suitable fluid pressure cylinder. The end of the rod is guided on a roller 266 on a bracket 265 (see Fig. 10'). By reciprocating the piston rod 264 a corresponding movement may be imparted to the sliding frame 241.

The movable frame 241 is built up of a web plate 250'' extending across the width of plate 240' and has vertical sides 268'. The vertical sides 268' provide supports for vertically movable clamping jaws 253 and 254. To the sides 268' are bolted cheek plates 255 to retain the clamping jaws 253 and 254 in position.

Supported on the frame 251' is a fluid pressure cylinder 252 having a depending rod 258 from which is suspended the upper clamping jaw 253, the side edges of which are provided with rack teeth as shown in Fig. 40. The lower jaw 254 is wider than the jaw 253, and has vertically extending sides, the inner edges of which are also provided with rack teeth. On each side of the jaw 253 are pinions 257 which engage the opposed rack surfaces. Upon reciprocation of the piston rod 258, the two jaws may thereby be reciprocated toward and from

each other. It will be noted that in this instance the plug bar is held against rotation inasmuch as no rotary movement is imparted to the tube while passing through the roll D.

For insuring the holding of the plug bar and plug in proper position during the rolling operation, we provide a vertical support 240'' at the end of plate 240', this vertical support being provided with a hood. Journalled at the sides of the vertical support 240'' at 243 are levers 244, each of which has one of their ends pivotally connected to links 250, which links in turn are pivoted to the webs 250' on the sliding frame 241. Journalled at the back of the support 240'' in brackets 246 is a rock shaft 245' having a depending operating lever 248a and upwardly extending cranks 248, which cranks are provided with pins 246' to engage the free ends of levers 244 to oscillate them. When the links and levers are in the position shown in Fig. 10, the end thrust on the plug bar 204 is transmitted to the movable frame 241, but this frame is held against rearward movement by the links and levers above described. By rocking shaft 245' and applying pressure to piston rod 264, the sliding frame 241 may be moved rearwardly.

The plug bar 204 is recessed to telescope 95 over the projecting end of the next succeeding plug bar (see Fig. 10) so that in effect a continuous plug bar may be provided. For renewing and changing the balls or plugs 203' on the plug bar 204, there is provided a plug manipulator adjacent the rolls D, and also adjacent each of the other pairs of rolls. This plug manipulating apparatus is shown in Figs. 9, 10 and 43. To the housing shoe 267 of the rolls D are connected the supports 209 which carry one end of rock shafts 210. Between the bottom housings 202 of the roll is the support 208 having upwardly projecting lugs which provide bearings for the opposite ends of shafts 210. On the two shafts 210 are sliding cranks 207 having relatively long hubs 207'. The outer ends of these cranks 207 are pivotally connected to links 206, the upper end of which links are pivotally connected to an extending plug trough 205. At the ends of the long sliding hubs or sleeves 207' are annular grooves to accommodate a cross head 213, the construction being such that while the cross head may be moved to reciprocate the sleeves 207' in unison along the shafts 210, it will not interfere with the rotation of the sleeves. At the middle of cross head 213 are lugs 213' which connect to link 214 by means of pin 213''. The other end of link 214 is pivotally connected to a lever 215 on a rock shaft 216 having its bearings 217 in the corner of housing shoe 267. Secured to the end of the shaft 216 is an operating lever 218. On the extreme ends of the two shafts 210

are mounted arms or cranks 211 pivotally connected at their lower ends by an operating rod 219.

The rod 219 is preferably operated by a fluid pressure cylinder, not shown. By this arrangement, the trough 5 may be moved longitudinally out of the roll housing, or vertically. The plugs are supported on the trough 205, which is normally in the lowered position shown in Fig. 43. When a tube has been rolled and a new plug is to be put on, the plug bar 204 is retracted and the trough 205 raised to a proper height, and a plug is placed in alignment with the bar and with the groove in the rolls through which the tube is being passed. The bar is then advanced until the plug is engaged thereby, whereupon, the trough 205 is lowered.

After the entire length of the tube has been received by the bar 204, the clamping jaws 253 and 254 are spread, and the tube is passed along to the next pair of rolls F (which rolls are similar to rolls D), the plug bar being continuous by reason of the telescoping ends. From the rolls F, it is received by the table G, which in all respects is similar to E. After passing through as many such operations as desired, the tube finally emerges from the last pair H also similar to the others, onto the run-out table I.

The run-out table I is constructed generally in the same way as table E or G, on parallel beams 301, and is transversely movable in the same way on inclined guides 373 by screws 374. In the table I, however, the clamping mechanism for the plug bar is not used and the edging or tube turning device is also eliminated. Journalled in bearings 333 are troughed rollers 316. These are driven through motor 328, gears 329, shaft 327, and miter gears 320' and 325, journals for shaft 327 being provided at 326.

In the table I, the plug bar 332 is secured at 340 to a cross head 319 (see Figs. 11, 12, 12', 46, 47, 48 and 49) having a depending portion 323, which portion has a laterally extending arm connected to a piston rod 336 of a pressure cylinder 317, the length of which cylinder and rod is substantially co-extensive with the length of the table I. At the side of the cross bar and pivoted at 331 are links 312' having their free ends provided with downwardly extending projections, as shown in Figs. 12 and 12'. These projections are adapted to ride over the inclined surface of the portion 324^a of the frame member 324 when the cross head is being moved to retracted position. They engage abrupt faces on the portions 324^a when a tendency is exerted to move them in the opposite direction. For disengaging these arms from the portion 324^a when it is desired to move the cross head rearwardly, a shaft 330 journalled at 321 and having arms

322 is provided. When the shaft 330 is rocked (as by manual means) the arms 22 lift the pivoted links sufficiently high for the projections thereon to clear the portion 324^a.

In operation, the cross head is held in its forwardmost position during the time a ball on the bar 332 is being engaged by a tube. The links 312' then act to prevent rearward movement of the cross head 319. When the entire length of the tube has been received upon the bar 332, and it is desired to discharge the completed tube, the links 312' are lifted in the manner hereinbefore described, and the cross head is moved rearwardly by operation of the cylinder 317, until the plug bar has been entirely withdrawn from the tube.

At 303 are semi-circular hoods or covers having arms thereon which are tightly secured to a longitudinal shaft 308 journalled along one side of the run-out table, in bearings 304' on frame members 304. Pivotedly supported in brackets 313 on the table frame is a fluid pressure jack 312 having a piston rod 339 which is connected to a crank 337 on the shaft 308 (see Fig. 48). By operation of this cylinder, all of the hoods 303 may be rocked upwardly to permit the tube to be removed.

For the purpose of ejecting the tubes after the plug bar has been withdrawn therefrom, we provide a series of arms or kickers 314^a secured at 315 to a second longitudinal rock shaft 309 carried in journals 304' on the frame members 304. Pivotedly mounted in brackets 311 on the table frame is a cylinder 310 having a piston 319 which connects to an arm 314 rigidly secured to shaft 309 (see Fig. 47). By operating cylinder 310, the kickers 314^a may be lifted to raise the tube which has heretofore rested on the guide plates 341. Upon the kickers 314^a being raised sufficiently, the tube will roll down them onto the inclined skids 340, and be delivered to the sawing or other apparatus, not shown.

From the foregoing, it will be seen that we have invented a practical system for the continuous rolling of tubes of various sizes without repassing the tubes through any of the rolls. With our apparatus, the pierced ingots or shells may be passed through the mill, one after another, as fast as they are delivered from the piercing mill. Thus, the tubes are formed before the metal has had a chance to cool, thereby reducing the liability of fracturing the tubes, as is often the case where the shell is cold before it is completely rolled into a tube by successive passes through the same rolls. Furthermore, a continuous plug bar is provided after the first rolling by means of the telescoping connections, so that the tube is kept from being bent while worked. By refer-

- ence to Fig. 50, which shows any one of the plugs or balls between the rolls with the shell X passing between the rolls, it will be seen that the plug does not expand 5 the tube, but merely maintains the proper diameter, and insures a proper finish for the interior of the tube, while the rolls reduce the thickness of metal from the outside.
- 10 While we have described a complete apparatus, we do not limit ourselves to the detail construction of such apparatus, as obviously various modifications and changes might be made in the embodiment of our invention which we have described.
- 15 What we claim is:
1. A rolling mill for the production of tubes comprising a series of rolls arranged in tandem, means for positively feeding the metal shell into the first roll, and means between the rolls for receiving the shell from the preceding roll and positively feeding it into the next roll.
  2. A rolling mill for the production of tubes from metal shells comprising a series of rolls arranged in tandem, said rolls being provided with various sizes of grooves for the production of tubes of different diameters, means for feeding the tube into any desired groove in the first pair of rolls, and means between each pair of rolls for receiving the shell from any groove in the preceding roll and feeding it into the corresponding groove of the following roll.
  3. A rolling mill for the production of tubes from metal shells comprising a series of rolls arranged in tandem, means for positively feeding the metal shell into the first roll, means between the rolls for receiving the shell from the preceding roll and directing and positively feeding it into the following one, a plug bar on said receiving means having a plug extending into operative relation with the preceding roll, and means for manipulating the plug bar for permitting the tube to pass over the plug end thereof and to be fed from the opposite end thereof.
  4. A rolling mill for the production of tubes from metal shells comprising a series of rolls arranged in tandem, means for feeding the metal shell into the first roll, and a continuous plug bar formed of telescoping sections extending from receiving position adjacent the first roll to receiving position adjacent the last one, means between each two rolls for normally holding the bar against longitudinal movement, said sections having plugs therein for cooperation with the rolls.
  5. A rolling mill for the production of tubes from metal shells comprising a series of rolls arranged in tandem, means for feeding the metal shell into the first roll, and a continuous plug bar formed of telescoping sections extending from receiving position adjacent the first roll to receiving position adjacent the last one, said sections having a sliding connection with each other and having removable plugs therein for cooperation with the rolls.
  6. A rolling mill for the production of seamless tubes from pierced shells comprising a receiving table for receiving the shells from a piercing mill, a plug bar on said receiving table, a thrust bearing for supporting one end of the plug bar, a clamp for engaging the ball end of the plug bar when the thrust bearing is inoperative, a feed trough for receiving the shell from the receiving table, a series of rolls arranged in tandem, means between the rolls for receiving the shell from the preceding roll and feeding it to the following one, and a run-out table for receiving the tube from the last roll of the series.
  7. A rolling mill for the production of seamless tubes from pierced shells comprising a series of rolls arranged in tandem, said rolls being provided with grooves of graduated sizes therein for the production of tubes of different diameters, a receiving table for receiving the shells from a piercing mill, a feed table between the receiving table and the first roll of the series, and normally in alinement with the receiving table, means for moving the feed table transversely to the rolls and receiving table to selectively feed the shell into any desired groove in said rolls, means on said feed table for receiving shells when the feed table is moved transversely out of alinement with the receiving table, means between the rolls for receiving the shell from any groove in the preceding roll and feeding it into the corresponding groove of the following one and a run-out table after the last roll of the series.
  8. A rolling mill for the production of seamless tubes from pierced shells comprising a series of rolls arranged in tandem, said rolls being provided with grooves of graduated sizes therein for the production of tubes of different diameters, a receiving table for receiving the shells from a piercing mill, a feed table between the receiving table and the first roll of the series, and normally in alinement with the receiving table, means for moving the feed table transversely to the rolls and receiving table to selectively feed the shell into any desired groove in said rolls, means on said feed table for receiving shells when the feed table is moved transversely out of alinement with the receiving table, transversely movable means between the rolls for receiving the shell from any groove of the preceding roll and feeding it into the cor-

responding groove of the following one, and a transversely movable run-out table after the last roll of the series.

9. A rolling mill for the production of 5 seamless tubes from pierced shells comprising a series of rolls arranged in tandem, said rolls being provided with grooves of graduated sizes therein for the production of tubes of different diameters, a receiving 10 table for receiving the shells from a piercing mill, a feed table between the receiving table and the first roll of the series, and normally in alignment with the receiving table, means for moving the feed table 15 transversely and vertically to the rolls and receiving table to selectively feed the shell into any desired groove in said rolls, means on said feed table for receiving shells when the feed table is moved transversely 20 out of alignment with the receiving table, transversely and vertically movable means between the rolls for receiving the shell from any groove of the preceding roll and feeding it into the corresponding groove 25 of the following one, and a transversely and vertically movable run-out table after the last roll of the series.

10. A rolling mill for the production of 30 seamless tubes from pierced shells comprising a series of rolls arranged in tandem, said rolls being provided with grooves of graduated sizes therein for the production of tubes of different diameters, a receiving table for receiving the shells from a piercing mill, a feed table between the receiving table and the first roll of the series, and normally in alignment with the receiving table, means for moving the feed table transversely to the rolls and receiving table to selectively feed 35 the shell into any desired groove in said rolls, means on said feed table for receiving shells when the feed table is moved transversely out of alignment with the receiving table, means between the rolls for receiving 40 the shell from any groove of the preceding roll and feeding it into the corresponding groove of the following one, and a run-out table after the last roll of the series, said means between the rolls and said run-out 45 table having plug bars associated therewith with plugs thereon for co-operation with the rolls.

11. A rolling mill for the production of 55 seamless tubes from pierced shells comprising a series of rolls arranged in tandem, means for receiving the shells and feeding them to the first roll of the series, a receiving table between each two rolls of the series for receiving the tube from one roll 60 and directing it through the other, a run-out table after the last roll of the series, plug bars associated with each receiving table between the rolls and with the run-out table, plugs removably carried by the bars, and plug manipulating mechanism for moving

new plugs into position adjacent the plug end of the bars.

12. A rolling mill for the production of 70 seamless tubes from pierced shells comprising a series of rolls arranged in tandem, means for receiving the pierced shells and feeding them to the first roll of the series, a receiving table between each two rolls of the series for receiving tubes from one and directing them into the other, means 75 on each of said receiving tables for turning the tubes after each rolling operation before passing them to the next roll, and a run-out table after the last roll of the series.

13. A rolling mill for the production of 80 seamless tubes from pierced shells comprising a series of rolls arranged in tandem, means for receiving the pierced shells and feeding them into the first roll of the series, a receiving table between each two rolls of 85 the series for receiving tubes from one roll and directing them into the other, and means between the rolls for rotating the tubes before passing them through the rolls.

14. A rolling mill for the production of 90 seamless tubes from pierced shells comprising a series of rolls arranged in tandem, means for receiving the pierced shells and feeding them into the first rolls of the series, a receiving table between each two rolls of 95 the series for receiving the tubes from one roll and feeding them to the other, plug bars having plugs thereon associated with the tables, plug bar clamps having opened and closed positions whereby a plug bar may be 100 clamped at the end opposite the plug when the clamp is closed or the tube passed off from said end when the clamp is opened, and means whereby said clamps may be reciprocated longitudinally. 105

15. A rolling mill for the production of 110 seamless tubes from pierced shells comprising a series of rolls arranged in tandem, means for receiving the pierced shells and feeding them into the first roll of the series, receiving tables between the rolls of the series, plug bars associated with the receiving tables, a run-out table after the last roll of the series, a plug bar associated with the run-out table, a support for the plug bar, and means whereby the support may be reciprocated to withdraw the bar from the tubes after they emerge from the last roll. 115

16. A rolling mill for the production of 120 seamless tubes from pierced shells comprising a series of rolls arranged in tandem, means for receiving the pierced shells and feeding them into the first roll of the series, receiving tables between the rolls of the series, plug bars associated with the receiving tables, a run-out table after the last roll of the series, a plug bar associated with the run-out table, a support for the plug bar, means whereby the support may be reciprocated to withdraw the bar from the tubes af- 125 130

ter they emerge from the last roll, and means for locking said support against reciprocation.

17. A rolling mill for the production of 5 seamless tubes from pierced shells comprising a series of rolls arranged in tandem, means for receiving the pierced shells and feeding them into the first roll of the series, receiving tables between the rolls of the series, plug bars associated with the receiving tables, a run-out table after the last roll of the series, a plug bar associated with the run-out table, a support for the plug bar, means whereby the support may be reciprocated to withdraw the bar from the tubes after they emerge from the last roll, means for locking said support against reciprocation, and means for removing the tube to one side after the plug bar has been withdrawn.

18. A rolling mill for the production of seamless tubes from metal shells comprising a series of rolls arranged in tandem, a plug bar for each roll having a plug thereon co-operating with the rolls, longitudinally reciprocable supporting means for each of the plug bars, and means whereby the shells may pass from one roll to the next over the plug bars.

30 19. The combination with a mill for the production of seamless tubes from pierced metal shells which mill includes a series of rolls arranged in tandem, of means co-operating therewith and for cooperation 35 with a piercing mill for receiving the shells from the piercing mill and feeding them to the first roll of the series.

20. The combination with a mill for the production of seamless tubes from pierced 40 metal shells which mill includes tube drawing rolls, of means cooperating therewith and for cooperation with a piercing mill for receiving the shells from the piercing mill and feeding them to the first roll of the series comprising a table, a thrust bearing at one end thereof for rotatably supporting a plug bar, and means whereby a shell received on said plug bar may be passed through the thrust bearing.

50 21. The combination with a mill for the production of seamless tubes from pierced metal shells, which mill includes tube drawing rolls, of means cooperating therewith and for cooperation with a piercing mill for receiving the shells from the piercing mill and feeding them to the first roll of the series comprising a table, a thrust bearing at one end thereof for rotatably supporting a plug bar, means whereby a shell received on said plug bar may be passed through the thrust bearing, and a roll feeding means onto which the shell is delivered after passing through the thrust bearing.

60 22. The combination with a mill for the production of seamless tubes from pierced

metal shells, which mill includes tube drawing rolls, of means cooperating therewith and for cooperation with a piercing mill for receiving the shells from the piercing mill and feeding them to the first roll of the series comprising a table, a thrust bearing at one end thereof for rotatably supporting a plug bar, means whereby a shell received on said plug bar may be passed through the thrust bearing, a roll feeding means onto which the shell is delivered after passing through the thrust bearing, and a pusher for pushing the shell from the plug bar to the feeding means.

23. The combination with a mill for the production of seamless tubes from pierced metal shells, which mill includes tube drawing rolls, of means cooperating therewith and for cooperation with a piercing mill for receiving the shells from the piercing mill and feeding them to the first roll of the series comprising a table, a thrust bearing at one end thereof for rotatably supporting a plug bar, means whereby a shell received on said plug bar may be passed through the thrust bearing, and mean for adjusting the table vertically.

24. The combination with a mill for the production of seamless tubes from pierced metal shells, which mill includes tube drawing rolls, of means cooperating therewith and for cooperation with a piercing mill for receiving the shells from the piercing mill and feeding them to the first roll of the series comprising a table, a thrust bearing at one end thereof for rotatably supporting a plug bar, means whereby a shell received on said plug bar may be passed through the thrust bearing, a roll feeding means onto which the shell is delivered after passing through the thrust bearing, a pusher for pushing the shell from the plug bar to the feeding means, and a pusher on the feed means for feeding the shell into the rolls.

25. A mill for the production of seamless tubing from pierced metal shells comprising a series of rolls arranged in tandem, a feeding table for feeding shells to the first roll of the series, receiving tables between the rolls for receiving the shells and feeding them to the next roll of the series, power driven feeding rollers on said feed table and receiving table, and a pusher on each of said receiving tables and the feed table for engagement with the shells to positively feed them.

26. A mill for the production of seamless tubes comprising a series of rolls arranged in tandem having plugs and plug bars co-operating therewith, and means including a continuous plug bar comprising slidably telescoping sections whereby the tubes from the rolls may pass from one roll to the next without changing their direction of travel.

65 27. A mill for the production of seamless

tubes from pierced shells comprising a series of rolls arranged in tandem, said rolls having grooves of different sizes therein, plugs and plug bars cooperating with the rolls, 5 and means whereby the shells may be selectively passed through the desired grooves in the successive rolls to produce tubes of the size desired.

28. A mill for the production of seamless tubes from pierced shells comprising a 10 series of rolls arranged in tandem, said rolls having grooves of different sizes therein, plugs and plug bars cooperating with the rolls, means whereby the tubes from the rolls 15 may pass from one roll to the next while

continuing their forward direction of travel, and means whereby the shells may be selectively passed through the desired grooves in the rolls for producing tubes of various diameters.

In testimony whereof we, the said JAMES J. HARKINS and OTTO F. ORMAN, have hereunto set our hands.

JAMES J. HARKINS.
OTTO F. ORMAN.

Witness as to James J. Harkins:

J. N. COOKE,

Witness as to Otto F. Orman:

W. D. MANSFIELD.
